DESIGN FOR A COMBINED REFRIGERATING AND DISPENSING CABINET

Raymond M. Cope, Chicago, Ill.

Application March 18, 1940, Serial No. 91,036

Term of patent 14 years

To all whom it may concern:

Be it known that I, Raymond M. Cope, a citizen of the United States, residing at Chicago, in the county of Cook and State of Illinois, have invented a new, original, and ornamental Design for a Combined Refrigerating and Dispensing Cabinet, of which the following is a specification, reference being had to the accompanying drawing, forming part thereof.

In the drawing:

The figure is a front perspective view of the combined refrigerating and dispensing cabinet, showing my design, it being understood that the rear and end of the cabinet not shown are plain.

I claim:

The ornamental design for a combined refrigerating and dispensing cabinet, as shown and described.

RAYMOND M. COPE.
